Primary Examiner — Michelle E. Wilson*(74) Attorney, Agent, or Firm* — Che-Yang Chen; Law Offices of Scott Warmuth(57) **CLAIM**

The ornamental design for a foldable laundry sorter, as shown and described.

DESCRIPTION

FIG. 1 is a perspective view of the foldable laundry sorter showing my new design;

FIG. 2 is a front and rear elevational view thereof;

FIG. 3 is a left and right side elevational view thereof;

FIG. 4 is a top plan view thereof;

FIG. 5 is a bottom plan view thereof;

FIG. 6 is a perspective view of the foldable laundry sorter that is partially folded;

FIG. 7 is a perspective view of the foldable laundry sorter that is completely folded;

FIG. 8 is a front and rear elevational view of FIG. 7;

FIG. 9 is a left and right side elevational view of FIG. 7;

FIG. 10 is a top plan view of FIG. 7;

FIG. 11 is a bottom plan view of FIG. 7;

FIG. 12 a perspective view of the fully extended foldable laundry sorter with laundry bags; and,

FIG. 13 is a top plan view of FIG. 12.
